UNITED STATES PATENT OFFICE

2,579,776

DRY SEAL PRESSURE TYPE GAS HOLDER

John W. Allen, Chicago, Ill., assignor to
John H. Wiggins, Chicago, Ill.

Application July 9, 1948, Serial No. 37,796

3 Claims. (Cl. 48—178)

1

This invention relates to a dry seal, piston-type gas holder or fluid storage apparatus of the particular kind disclosed in my Patent No. 2,554,767, dated May 29, 1951, in which the sealing means between the piston and the container side wall comprises a plurality of flexible elements, usually constructed of gas-tight fabric arranged at opposite sides of and attached to a vertically-movable, annular member that serves as a backing and reinforcing device for the flexible piston sealing means during the cycle of operations of the piston. During the first portion of the upward travel of the piston, the said vertically-movable backing annular member remains at rest on the bottom of the container, due to the weight of said member, and as the piston moves upwardly, the "inner" flexible piston sealing element (the one between the piston and the inner face or side of said vertically-movable backing member) is progressively stripped off an annular backing member carried by the piston and is progressively applied to the previously mentioned vertically-movable backing member. After the inner flexible sealing element has been applied to said vertically-movable backing member, said member starts to move upwardly with the piston, due to the engagement of the piston with a part on said member, and during the remainder of the upward travel of the piston, and while the piston is at the end of its upward stroke, said vertically-movable backing member remains in fixed relationship with the piston and serves as a backstop and reinforcing device for the inner flexible sealing element. It will thus be seen that in an apparatus of the kind above described it is necessary that the height or depth of the vertically-movable backing member above the point of attachment of the inner sealing element must be equal to or in excess of the length of the inner sealing element, due to the fact that it serves as a backstop for the said inner sealing element, during the upward stroke of the piston and when the piston is at the end of its upward stroke. Also in such an apparatus, means must be provided for causing the piston to pick up and impart upward movement to the vertically-movable backing member after the inner flexible sealing element has been applied to said member.

One object of my invention is to provide a gas holder of the general kind above referred to, which is of such construction or design that the vertically-movable, annular backing member can be made of considerably less height or depth than the inner flexible sealing element, thereby

2

effecting a substantial saving in the quantity of steel used in the construction of said member.

Another object is to provide a gas holder of the general kind referred to, which is of such construction or design that the weight or load of the vertically-movable backing member is not imposed on the piston during the upward travel of the piston, thereby approaching a constant pressure on the gas stored in the holder during the full volume change (from empty to full) and also reducing the cost and simplifying the construction of the apparatus by eliminating the pick-up and supporting means between the piston and the vertically-movable backing member. 10 And still another object of my invention is to provide a gas holder of the general kind above referred to in which both or all fabric elements of the piston sealing means are backed up and reinforced by the container side wall when the 20 storage chamber of the holder is full of gases. Other objects and desirable features of my invention will be hereinafter pointed out.

Figure 1 of the drawings is a vertical transverse sectional view of a dry seal, piston-type gas holder embodying my present invention, showing the piston in its lowermost position.

Figure 2 is a fragmentary sectional view, showing how the vertically-movable, annular backing member rises or moves upwardly during the first 30 part of the upward travel of the piston.

Figure 3 is a similar view, showing how the inner flexible sealing element is applied to the container side wall after the upward movement of said vertically-movable backing member has been arrested.

Figure 4 is a vertical, transverse sectional view, illustrating my invention applied to a container whose side wall has an inwardly off-set portion at its upper end.

Figures 5 and 6 are fragmentary sectional views, illustrating the operation of applying the inner flexible sealing element to the off-set portion of the side wall.

Figure 7 is a fragmentary sectional view, illustrating how a counterweighted mechanism can be combined with the vertically-movable, annular backing member in instances where the pressure uplift on the flexible piston sealing means is not sufficient to raise or move said backing member upwardly; and

Figure 8 is a vertical transverse sectional view of a gas holder constructed in accordance with my present invention and equipped with a piston sealing means that comprises three fabric sealing elements which co-act with two vertically-

movable, annular backing and reinforcing members.

In the accompanying drawings A designates the bottom of the container of a dry-seal, piston-type gas holder or fluid storage apparatus, C designates the side wall of said container, D designates the roof or top of the container, and B designates the vertically-movable piston in said container which forms the top wall of the gas storage chamber. The space between the piston and the container side wall is sealed by two flexible curtain-like sealing elements F' and F², usually constructed of gas-tight fabric, arranged on opposite sides of and attached to a vertically-movable, annular member E' that forms part of a backing and reinforcing structure for the flexible piston sealing means, and which preferably also comprises an annular backstop member E² on the piston, disposed in concentric relation with said backing member E'. As shown in the drawings, the "outer" sealing element F' has its outer edge attached to an intermediate portion of the container side wall, and has its inner edge attached to the lower end of the vertically-movable backing member E'. The "inner" flexible sealing element F² is attached at its outer edge to the upper end of the vertically-movable backing member E', and is attached at its inner edge to the lower end or bottom edge of the annular backing member E² carried by and projecting upwardly from the periphery of the piston. The vertically-movable backing member is constructed of steel, aluminum or some other rigid or inflexible material, and is preferably made of such weight that the pressure uplift on the outer sealing element F' is sufficient to cause the annular backing member E' to rise or move upwardly with the piston during the first portion of the upward stroke of the piston.

When the piston B is at the end of its downward stroke, the internal pressure of the storage chamber presses the outer sealing element F' snugly against the outer side of the vertically-movable backing member E', and also presses the inner sealing element F² snugly against the backing member E² carried by the piston, as shown in Figure 1. When the piston starts to move upwardly, the backing member E' rises with the piston, thereby causing the outer sealing element to be stripped off the backing member E' and progressively applied to the container side wall C, as shown in Figure 2. After the backing member E' has reached such a height or elevation that the sealing element F' is effectively backed up by the container side wall and is in its fully extended position shown in Figure 3, the upward movement of the backing member E' is arrested by the pull exerted on said member by the sealing element F'. The piston, however, continues its upward movement, with the result that the inner sealing element F² is stripped off the backing member E² carried by the piston, and is progressively applied to the container side wall C, the upward movement of the piston together with the internal pressure of the storage chamber causing the sealing element F² to be rolled outwardly over the top edge of the vertically-movable backing member E' and forced into snug engagement with the container side wall, as shown in Figure 3, at a point above the outer sealing element F'. The inner sealing element F² is made with some fullness, and in the form of my invention illustrated in Figures 1, 2 and 3 is so designed that when it is rolled outwardly over the top edge of the backing member E',

after said backing member has come to rest, the fabric of which said sealing element F² is constructed will stretch sufficiently to permit the major portion of said sealing element to lie flat against the container side wall. During the downward stroke of the piston, the inner sealing element F² is stripped off the container side wall and progressively applied to the backing member E² carried by the piston, and thereafter the outer sealing element F' is stripped off the container side wall and progressively applied to the backing member E'. From the foregoing it will be seen that in a gas holder of the construction above described the container side wall is used as an abutment surface for both fabric elements of the piston sealing means when the storage chamber is full, thereby enabling the depth or height of the vertically-movable backing member E' to be greatly reduced, and consequently, effecting a considerable saving in the quantity of metal or other rigid material used in the construction of said backing member. Such a gas holder is also desirable, in that the particular construction and arrangement of the two fabric sealing elements F', F² and the vertically-movable backing member E', eliminates the necessity of lifting said backing member by the piston, during the full volume change from empty to full.

Figures 4, 5 and 6 illustrate another form of my invention, wherein the container side wall is provided at its upper end with an inwardly offset portion disposed in such relationship with the inner flexible sealing element F² and with the vertically-movable backing member E', that the sealing element F² is not stretched or rolled outwardly over the top edge of the backing member E' in the operation of applying said sealing element to the container side wall during the upward stroke of the piston. In the gas holder shown in Figures 4, 5 and 6, the container side wall comprises a cylindrical lower portion C', a cylindrical upper portion C² of less diameter than said lower portion, and an inward off-set X that joins said lower and upper portions C' and C² together. During the upward travel of the piston the vertically-movable backing member E' comes into contact with and is arrested by the off-set X in the container side wall, and thereafter, as the piston continues its upward movement, the inner sealing element F² is progressively applied to the inner face of the reduced upper portion C² of the side wall, as shown in Figures 5 and 6.

In a gas holder embodying my invention, any suitable means can be used to keep the piston level during its upward movement, such, for example, as a series of weights K connected to diametrically opposite sides of the piston by means of cables H' and H² that travel over sheaves J', J² and J³ mounted on the roof D of the container, as shown in Figure 4. Although the vertically-movable, annular backing member E² is full floating, said member is automatically kept level by the outer sealing element F' and by the offset X in the container side wall, when said member E' reaches its uppermost position.

In instances where the pressure uplift on the outer flexible sealing element F' is not sufficient to cause the vertically-movable, annular backing member E' to rise during the first portion of the upward stroke of the piston, a series of counterweights N can be connected to said backing member by cables O traveling over sheaves M, as shown in Figure 7 of the drawings.

Figure 8 of the drawings illustrates an appara-

tus similar to that shown in Figure 4, but equipped with a piston sealing means that comprises three concentrically-arranged, flexible sealing elements F' , F^2 and F^3 , combined with a backing and reinforcing structure that comprises an annular backing member E^2 on the piston, and a plurality of concentric, vertically-movable, annular backing members E' and E^3 . In such an apparatus the container side wall is preferably composed of three cylindrical shells C' , C^2 and C^3 of different diameters, connected to each other by two offsets X and X' .

Having thus described my invention, what I claim as new and desire to secure by Letters Patent is:

1. In a fluid storage apparatus, the combination of a container having a vertical side wall that comprises a lower cylindrical portion, a cylindrical upper portion offset inwardly from said lower portion and rigidly connected to same by a substantially horizontally-disposed part that serves as a stop, a vertically-movable piston in said container spaced away from the container side wall and provided with a rigid cylindrical backing member attached to the piston and projecting upwardly from the top side of same, a vertically-shiftable backing member of tubular form arranged in concentric relation with the backing member on the piston and disposed at a point below and in vertical alignment with the previously mentioned horizontally-disposed stop part of the container side wall, an outer fabric sealing element of approximately annular form having one of its edges attached to the lower cylindrical portion of the container side wall and its other edge attached to the lower end of said vertically-shiftable backing member, and an inner fabric sealing element of approximately annular form having one of its edges attached to the upper end of said vertically-shiftable backing member and its other edge attached to the piston adjacent the lower end of the rigid backing member that projects upwardly from the top side of the piston, the said outer sealing element being adapted to be forced into snug engagement with the lower portion of the side wall and the inner sealing element adapted to be forced into snug engagement with the inwardly-offset upper portion of the container side wall by the internal pressure of the storage chamber, during the upward movement of the piston.

2. A fluid storage apparatus, comprising a container having a side wall, a vertically-movable piston in said container that forms the top wall of the storage chamber of the apparatus, an annular backing member rigidly attached to the piston and projecting upwardly from the top side of same, a second annular backing member arranged in the space between the piston and the container side wall and adapted to move vertically relatively to the piston and to the side wall, a flexible outer sealing element attached to the container side wall and to the lower end of said vertically-movable backing member, and a flexible inner sealing element attached to the upper end of said vertically-movable backing member and to the piston adjacent the lower end of the backing member on the piston, said backing members and sealing elements being combined in such relationship that when the piston is at the end of its downward stroke the pressure in the storage chamber forces the outer sealing element into snug engagement with the vertically-movable

backing member and also forces the inner sealing element into snug engagement with the backing member on the piston, and during the upward travel of the piston, said annular backing members will move relatively to each other into such positions as to cause the outer sealing element to be applied to the container side wall and thereafter cause the inner sealing element to be applied to the container side wall at a point considerably higher than the horizontal zone in which said outer sealing element lies against the container side wall, the container side wall being provided with two cylindrical portions of different diameters, the larger one of which is adapted to serve as a back stop for the outer sealing element and the smaller one of which is adapted to serve as a back stop for the inner sealing element when the storage chamber is full of gas.

3. A fluid storage apparatus, comprising a container having a side wall, a vertically-movable piston in said container that forms the top wall of the storage chamber of the apparatus, an annular backing member rigidly attached to the piston and projecting upwardly from the top side of same, a second annular backing member arranged in the space between the piston and the container side wall and adapted to move vertically relatively to the piston and to the side wall, a flexible outer sealing element attached to the container side wall and to the lower end of said vertically-movable backing member, and a flexible inner sealing element attached to the upper end of said vertically-movable backing member and to the piston adjacent the lower end of the backing member on the piston, said backing members and sealing elements being combined in such relationship that when the piston is at the end of its downward stroke the pressure in the storage chamber forces the outer sealing element into snug engagement with the vertically-movable backing member and also forces the inner sealing element into snug engagement with the backing member on the piston, and during the upward travel of the piston, said annular backing members will move relatively to each other into such positions as to cause the outer sealing element to be applied to the container side wall and thereafter cause the inner sealing element to be applied to the container side wall at a point considerably higher than the horizontal zone in which said outer sealing element lies against the container side wall, the container side wall comprising two cylindrical portions of different diameters joined by a portion disposed so as to serve as a stop that arrests the upward movement of said second vertically-movable annular backing member, prior to completion of the upward stroke of the piston.

JOHN W. ALLEN.
